UNITED STATES PATENT OFFICE.

JOSEPH T. COMMOSS, OF NEW YORK, N. Y.

DESIGN FOR A MATCH.

SPECIFICATION forming part of Design No. 25,612, dated June 9, 1896.

Application filed March 31, 1896. Serial No. 585,659. Term of patent 7 years.

To all whom it may concern:

Be it known that I, JOSEPH T. COMMOSS, a citizen of the United States, residing at New York, in the county of New York and State 5 of New York, have invented and produced a new and original Design for Matches, of which the following is a specification, reference being had to the accompanying drawings, forming a part thereof.

My new and original design is fully disclosed in the following specification, of which the accompanying drawings form a part, in which—

Figure 1 is a side view of a match formed 15 according to my design, and Fig. 2 an edge view thereof, these two views being deemed necessary to fully illustrate my design.

The leading feature of my design consists 20 of a flat body portion A of a rectangular form, from which projects a tapering extension B, the end of which culminates in an enlargement or head C, the lines forming the side of

said extension being inwardly curved. Upon the sides of the body portion A are formed two sets of parallel diagonal lines, as shown 25 at D and F, and a space between said lines is plain, while at the outer side thereof are formed triangular figures G, within which are formed other triangular figures H, said figures being formed by straight lines. 30

Having fully described my new and original design for matches, I claim as new and desire to secure by Letters Patent—

The design for a match herein shown and described. 35

In testimony that I claim the foregoing as my invention I have signed my name, in presence of the subscribing witnesses, this 28th day of March, 1896.

JOSEPH T. COMMOSS.
